UNITED STATES PATENT OFFICE.

OTTO PAUL RIEDEL, OF WEST NEW YORK, NEW JERSEY, ASSIGNOR TO WEST SHORE EMBROIDERY COMPANY, OF WEST NEW YORK, NEW JERSEY, A CORPORATION OF NEW JERSEY.

DESIGN FOR EMBROIDERED TRIMMING.

48,460.

Specification for Design.

Patented Jan. 11, 1916.

Application filed November 26, 1915. Serial No. 63,683. Term of patent 3½ years.

To all whom it may concern:

Be it known that I, OTTO PAUL RIEDEL, a citizen of Germany, residing in West New York, Hudson county, State of New Jersey, have invented a new, original, and ornamental Design for Embroidered Trimming, of which the following is a specification, reference being had to the accompanying drawing, forming a part thereof.

The figure is a plan view of a portion of the trimming, showing my new design.

Copies of this patent may be obtained for five cents each, by addressing the "Commissioner of Patents, Washington, D. C."

I claim:

The ornamental design for embroidered trimming, as shown.

In testimony whereof I have signed this specification in the presence of two subscribing witnesses.

OTTO PAUL RIEDEL.
